UNITED STATES PATENT OFFICE.

BENJAMIN PUTTERMAN, OF BROOKLYN, NEW YORK, ASSIGNOR TO AMERICAN AUTO LAMP CO., INC., A CORPORATION OF NEW YORK.

DESIGN FOR A SMOKER'S RECEPTACLE.

Application filed March 21, 1928. Serial No. 25,940. Term of patent 14 years.

To all whom it may concern:

Be it known that I, BENJAMIN PUTTERMAN, a citizen of Poland, residing in the borough of Brooklyn, county of Kings, city and State of New York, have invented a new, original and ornamental Design for a Smoker's Receptacle, of which the following is a specification, reference being had to the accompanying drawings, forming a part thereof.

Fig. 1 is a plan view of a smoker's receptacle, illustrating my new design.

Fig. 2 is a perspective view thereof.

I claim:

The ornamental design for a smoker's receptacle, substantially as shown.

This specification signed this 19th day of March, 1928.

BENJAMIN PUTTERMAN.
